MANCHA STORAGE BATTERY LOCOMOTIVE COMPANY, OF ST. LOUIS, MISSOURI, A
CORPORATION OF DELAWARE.

MULTIPLE FUSE AND FUSE HOUSING.

Application filed October 26, 1922. Serial No. 597,220.

To all whom it may concern:

Be it known that we, JOSEPH TEIPEL and WILLIAM F. EXNER, citizens of the United States, residing in the city of St. Louis, State of Missouri, have invented a certain new and useful Improvement in Multiple Fuses and Fuse Housings, of which the following is a full, clear, and exact description, such as will enable others skilled in the art 10 to which it appertains to make and use the same.

This invention relates to a multiple fuse and fuse housing.

One object of our invention is to provide 15 a multiple fuse of novel construction that can be operated easily to bring a perfect fuse into operative position after one of the other fuses has ruptured, without opening the housing that encases the fuses.

Another object is to provide a practically 20 gas and flame-proof fuse housing of simple design and inexpensive construction that can be opened easily to inspect or renew the fuse arranged inside of the housing. Other 25 objects and desirable features of our invention will be hereinafter pointed out.

Figure 1 of the drawings is a vertical 30 longitudinal sectional view of a multiple fuse and fuse housing constructed in accordance with our invention.

Figure 2 is a transverse sectional view, taken on the line 2—2 of Figure 1; and

Figure 3 is a perspective view of the fuse 35 housing, shown in Figure 1.

Referring to the drawings which illustrate 40 the preferred form of our invention, A designates a plurality of fuses, preferably fuses of the kind known commercially as "fuse links," B designates a rotatable carrier on which the fuse links A are mounted, and C designates a pair of spring brushes or contacts mounted on brush holders D to which the wires E of an electric circuit are connected. The fuse carrier B is rotatably 45 mounted in a housing F that is substantially gas and flame-proof, and said carrier is provided with an operating handle G arranged on the exterior of the housing F that is adapted to be turned so as to bring the fuse 50 links A into and out of operative relationship with the brushes C.

The housing F may be of any preferred

construction, but it preferably consists of a hollow casting having an opening in its front wall that is surrounded by a flange 1 55 through which the fuse carrier can be inserted in and removed from the housing, and having an opening in its top wall surrounded by a flange 2 that provides access to the fuses A mounted on the carrier B. 60 The openings just referred to are normally closed by caps 1^a and 2^a that have internally screw-threaded flanges which are adapted to be screwed onto the flanges 1 and 2, respectively, on the housing F. By constructing the housing in this manner we obtain a housing that is substantially flame and gas-proof, but which can be opened easily to inspect or renew the fuses. In order to prevent an unauthorized person from tampering 65 with the fuses in the housing F means is provided for locking the closures 1^a and 2^a in operative position on the housing, the means herein illustrated for this purpose consisting of a padlock or other sealing device H that is adapted to be arranged in engagement with perforated ears 1^b and 2^b on the caps 1^a and 2^a, as shown in Figure 3. Preferably, each of said caps is provided 70 with a plurality of perforated ears so as to compensate for wear on the co-operating screw threads on the caps and housing, and thus enable said caps to always be set in such a position that two of the co-operating ears on same will line up close enough to enable both of said ears to be locked by a single padlock or sealing device. 75

The carrier B is normally set in such a position that one of the fuse links A thereon is in operative relationship with the 80 brushes or contacts C, thereby completing the circuit of which the wires E form a part. When one of the fuses ruptures it is only necessary to turn the operating handle G of the fuse carrier so as to bring a perfect fuse into operative relationship with the brushes C. If it is desired to open the circuit the carrier B is moved into such a position that no fuse A on the carrier will be in operative relationship with the brushes C. Various means can be used for indicating the position of the fuse carrier, or, in other words, to show whether one of the 85 fuse links on the carrier is in operative re- 90

lationship with the brushes C or to show whether all of the fuse links are inoperative, but we prefer to provide the operating handle G with a pointer 3 that co-operates 5 with devices 4 on the outer side of the cap 1^a to indicate when one of the fuse links is in operative relationship with the brushes C and which co-operates with devices 5 on the outer side of the cap 1^a to indicate when 10 all of the fuse links on the carrier are in inoperative relationship with the brushes C. In the embodiment of our invention herein illustrated the carrier B is provided with three fuse links and the cap 1^a is provided 15 with three devices 4 arranged in symmetrical relation with and between three devices 5, each of the devices 4 being designated by the letter "F" so as to indicate that when the pointer 3 is in alignment with one of 20 the devices 4, one of the fuse links A on the carrier will be in firing position or in operative relationship with the brushes, and each of the devices 5, being designated by the letter "N," so as to indicate that when 25 the pointer 3 is in alignment with one of the devices 5, all of the fuse links on the carrier will occupy a neutral position. The fuse carrier B is retained in adjusted position by a locking means which is herein illustrated as consisting of a spring-pressed 30 ball 6 on the operating handle G that is adapted to seat in one of a plurality of recesses 7 formed in the outer face of the cap 1^a against which the inner end of the operating handle G bears.

The particular design and construction of the fuse carrier B is immaterial, so far as our broad idea is concerned, but we prefer to construct said carrier from a cylindrical 40 core of wood or other suitable insulating material 8 connected to a shaft 9 and provided at its opposite ends with two sets of metallic segments 10 arranged between segments 11 of insulating material, said segments 10 and 11 projecting radially from the core. Each of the metallic segments is provided with an extension 10^a arranged 45 in longitudinal alignment with the extension 10^a of one of the metallic segments 10 at the opposite end of the carrier. The fuse links A are detachably connected to a pair 50 of extensions 10^a by fastening devices 12 that can be removed easily when it becomes necessary to replace the fuse links. In view 55 of the fact that the extensions 10^a are formed by projections or raised members on the exterior of the core, the fuse links will be held spaced away from the outer surface of the core. The brush holders D are carried 60 by a block of insulating material 13 and are so arranged that the brushes C are in alignment with the two groups of segments 10 and 11 at the opposite ends of the fuse carrier B. When the fuse carrier is set 65 in such a position that the brushes C bear

upon two opposed metallic segments 10 of the carrier, the circuit will be closed by the fuse link A connected to the extensions 10^a of that particular pair of metallic segments 10. At this time the pointer 3 on the operating handle G of the fuse carrier will stand opposite one of the devices 4 on the cap 1^a, thus indicating that one of the fuses is in firing position. When the carrier B is set in such a position that the brushes C 70 bear upon a pair of opposed insulating segments 11 on the carrier, the circuit of which the wires E form a part will be open. At such times the pointer 3 on the operating handle stands opposite one of the devices 5, 75 thus indicating that all of the fuses on the carrier are in neutral position. The shaft 9 of the carrier B projects outwardly through a hole in the cap 1^a and the operating handle G is secured to said shaft by a pin or other suitable means 14, as shown in Figure 1, the opposite end of said shaft being journaled in a bearing 15 on the inside 80 of the housing F. In order to produce a gas and flame-tight joint around the shaft 9, the cap 1^a is provided with packing rings 16 that surround said shaft.

In a device of the construction above described the blowing of a fuse causes only a momentary interruption of the electric circuit with which the device is used, due to the fact that a perfect fuse can be brought into operative relationship with the brushes C by simply turning the operating handle G of the fuse carrier far enough to bring the metallic segments 10 to which said fuse is connected into position to be engaged by said brushes. The position of the fuse carrier with relation to the brushes C is indicated at all times by the pointer on the operating handle G, and the cooperating devices 4 and 5 on the cap 1^a of the housing, and still another desirable feature of such a device is that the housing of same is substantially flame and gas-proof, but is capable of being opened easily to inspect or renew the fuses inside of the housing. While the device is capable of general use, it is particularly adapted for use on storage battery mine locomotives, due to the fact that it comprises a plurality of fuses that can be rendered operative and inoperative without opening up the housing of the device; the housing is constructed in such a way that it is impossible for a flame or electric spark to escape therefrom and thus ignite a gas leak in a mine, and it is impossible for the operator in charge of the locomotive to open the housing without breaking the sealing device H, thereby advising his superior or the person authorized to open the housing that the operator has done something which he was forbidden to do. And still another desirable feature of a fuse housing of the construction above described is that it can be opened 100

quickly and easily by an authorized person to inspect or renew the fuses or bodily remove the fuse carrier from the housing.

Having thus described our invention, 5 what we claim as new and desire to secure by Letters Patent is:

1. A multiple fuse, comprising a housing, a carrier in said housing provided with a plurality of fuses, one opening in said housing through which said fuses can be inspected, another opening in said housing through which the carrier can be removed from the housing, movable closures for said openings, and means for locking said closures together. 10
2. A multiple fuse, comprising a housing, a rotatable carrier in said housing provided with a plurality of fuses, removable closures for openings in said housing connected to the housing by screw threads, an operating shaft for said carrier projecting through one of said closures, and means for producing a tight joint around the portion of the shaft that projects through said closure. 15
3. A multiple fuse, comprising a housing, 20 a removable closure for an opening in said housing, and a rotatable fuse carrier permanently combined with said closure and adapted to be inserted in the housing through the opening with which said 25 closure co-operates. 30
4. A multiple fuse, comprising a closed housing provided with two openings surrounded by externally screw-threaded flanges, removable caps screwed onto said flanges, means for preventing an unauthorized person from removing said caps, a shaft rotatably mounted in one of said caps, a carrier on said shaft provided with a plurality of fuses, and an operating device connected to said shaft at a point on the outside of the cap in which the shaft turns. 35
5. A multiple fuse, comprising a housing provided with two openings surrounded by externally screw-threaded flanges, caps 40 screwed onto said flanges and provided with means whereby both caps can be locked by the same sealing device, a rotatable shaft in one of said caps provided with a carrier, a plurality of fuses detachably connected to said carrier, an operating device on said shaft arranged on the outside of the cap in which the shaft is journaled, a locking means co-operating with said operating device to hold the carrier in adjusted position, and co-operating means on said operating device and on the exterior of said cap for indicating the position of the carrier in the housing. 45

JOSEPH TEIPEL.
